MISTLETOE HOLDER

Stanley Walczak, 26324 State Road 2, South Bend, Ind.

Filed Dec. 21, 1960, Ser. No. 63,294

Term of patent 14 years

(Cl. D29—1)

FIG. 1

Des. 191,048

PAGE 2

FIG. 2

I claim:

The ornamental design for a mistletoe holder, substantially as shown.
